SUCTION ROLL FOR PAPER-MAKING MACHINES

Herbert Holden, Sheffield, England, assignor to Beloit Iron Works, Beloit, Wis., a corporation of Wisconsin

Application February 3, 1955, Serial No. 486,008

Claims priority, application Great Britain
February 22, 1954

11 Claims. (Cl. 92—53)

This invention relates to the suction rolls of paper-making machines, i. e., rolls having a perforated shell rotatable about an internal suction box with arcuate sealing strips towards the ends of the shell and longitudinal sealing strips to define the arcuate width to which suction is applied from the mouth of the box through the perforations of the shell to a paper web directed over the outside of the shell. The suction box is supported at its ends beyond the ends of the shell, usually with adjustable compression springs urging it in a direction to effect contact between the sealing strips and the shell, the initial degree of contact being governed by adjustable limit stops in opposition to the springs. When suction is applied it operates to draw the box and the arcuate portion of the shell embraced by the mouth of the box between the longitudinal strips towards each other, thus adding to each strip a load amounting to approximately one-half of the product of the projected embraced area of the shell and the amount of negative pressure per unit of area corresponding to the applied suction. The greater the embraced arc, the greater the load on each strip per unit of length of the box; and the greater the roll-length the greater the load.

The suction being uniformly distributed, and the suction box being eased from the shell by the limiting stops at the end of the box, the suction box operates as a beam subjected to a uniformly distributed load and when in operation tends to deflect towards the portion of the shell embraced between its longitudinal sealing strips (or "deckles"). As a result, greater load is applied to the centre of each strip than to its ends. Although it is known to provide for radial movement of the strips with respect to the edges of the box and to urge the strips outwardly by springs into floating engagement with the shell, such a construction is complicated and adds substantially to the already considerable weight of the box. It is therefore advantageous to have the strips fitting the full depth of radial slots in the edges of the box. However, this means that the strips must follow the deflection of the box, and the greater load towards the centre results in wearing of the strip to a greater degree at the centre than at the ends. When suction is removed from the box, the absence of deflecting force arising from suction leaves the centre of the strip out of contact with the shell, so that on re-application of suction there is a gap along the strip through which the suction can draw air, and in some cases the gap may be so large that the suction cannot pull the box back into contact with the shell. The wider the mouth of the box, the greater the suction loading to produce box deflection and strip wear and the greater the resultant gap.

An object of the invention is to reduce the deflection arising from the applied suction, and therefore to reduce the tendency to greater wear towards the centre of fixed longitudinal sealing strips. A further object is to reduce the power necessary to drive the roll.

According to the present invention, a beam-like suction box for a suction roll of a paper-making machine with

2

fixed longitudinal sealing strips along the edges of the suction compartment of the box to contact the roll shell is provided with a longitudinal beam secured at its ends only to the suction box and with a further longitudinal suction compartment in communication with the main suction compartment, one boundary surface of this further compartment nearer the sealing edges at the mouth of the main compartment being constituted by a wall of the suction box itself and the other boundary surface farther from the sealing edges of the main compartment being connected to the longitudinal beam over the length of that beam.

The beam support may, however, be external to the suction box, and is then preferably duplicated, two flanged beams lying alongside the sides of the box. Thus the ends of one flange of each beam may be secured externally to a body portion of the box of hollow generally rectangular section, and the depth of the beams may be such that the other flange of each extends beyond the outer wall of the hollow section, to be connected along their length to the boundary surface of the further suction compartment, which surface extends between the beams.

With that boundary surface in the form of a plate with a flexible seal round its entire periphery and the outer wall of the hollow section, that outer wall completes the further compartment. In this case also, the communication between the compartment may consist of a tube passing uninterruptedly through the hollow section.

The principle of the invention, and two embodiments of that principle, will now be described in greater detail with reference to the accompanying drawings, in which—

Figures 1 to 8 are diagrammatical illustrations comparing the results obtained in practice using a suction box according to the invention (Figures 5 to 8) with the results obtained using a suction box of conventional design (Figures 1 to 4);

Figure 9 is a fragmentary vertical section on the axis of one form of suction box according to the invention and showing the method of supporting the suction box within a suction roll;

Figure 10 is a section on the line 10—10 of Figure 9;

Figure 11 is a side elevation of another form of suction box according to the invention; and

Figure 12 is a vertical section on the line 12—12 of Figure 11.

Figure 1 shows a transverse section through a suction box 10 of conventional design having arcuate sealing strips (or "deckles") 11 towards its ends and longitudinal sealing strips 12 to define the arcuate width to which suction is applied from the mouth of the box through the perforations of a roll shell 13 to a paper web (not shown) directed over the outside of the shell. The body of the box 10 is of rectangular section 14, suction being applied to the defined arc from a chamber 15 having a connection 16 (Figure 2) to a vacuum pump (not shown). The suction box 10 is supported at its ends beyond the ends of the shell 13, with adjustable compression springs urging it in a direction to effect contact between the sealing strips 11, 12 and the shell, the initial degree of contact being governed by adjustable limit stops in opposition to the springs, e. g. in the manner shown in Figure 9. In Figures 2 to 4 and 6 to 8, the spring reactions on the roll are indicated at R and the stop reactions are indicated at P, as and when they are effective.

When the suction box 10 is initially installed within the roll shell 13, the edges carrying the sealing strips 12 are formed to be parallel to the axis of the roll shell 13 when the box supported at its two ends deflects downwardly under its own weight with no suction applied, as is shown in the longitudinal sectional drawing of Figure 2. With no suction applied and the initial degree of

contact between the sealing strips and shell set at the minimum necessary for effective sealing, the total of the spring reactions R will be slightly more than the weight of the box. When suction is applied to the chamber 15 it operates to draw the box 10 and the arcuate portion of the shell 13 embraced by the box between the longitudinal strips 12 towards each other, thus adding a further load to each strip. As the suction is uniformly distributed over the length between the arcuate sealing strips 11, the suction box operates as a beam subjected to a uniformly distributed load with reactions P at its ends (Figure 3) and deflects towards the shell 13 by an amount a roughly midway between the arcuate strips 11. As a result, greater load is applied to the centre of each strip than to its ends. The wear at the centre of the strips is consequently greater, and the power required to drive the roll greatly increased. Further, when the application of suction to the chamber 15 is stopped, and the box 10 again deflects under its own weight, whilst supported solely by the spring reactions R (Figure 4), owing to the wear being greater at the centre of the sealing strips than at the ends, the absence of deflecting force arising from suction leaves the centres of the strips 12 out of contact with the shell 13 by an amount b , so that on re-application of suction there is a gap along the strips through which the suction can draw air into the chamber 15, and in some cases the gap may be so large that the suction cannot pull the box 10 back into sealing contact with the shell 13. The wider or longer the mouth of the box, the greater the suction loading producing box deflection and strip wear and the greater the resultant gap.

Figures 5 to 8, corresponding to Figures 1 to 4, show diagrammatically a suction box according to the invention. The suction box 17 with fixed longitudinal sealing strips 18 and arcuate sealing strips 19 towards the ends of the box forming a suction compartment 20, is provided with a longitudinal beam 21 secured at its ends only (represented diagrammatically at 22) to the suction box and with a further longitudinal suction compartment 23 communicating through tubes 24 with the main suction compartment 20, with the boundary surface of the compartment 23 nearer the sealing edges of the compartment 20 being the lower wall 25 of the rectangular section 26 of the box 17 itself and the other boundary surface farther from the sealing edges of the compartment 20 being a plate 27 connected to the beam 21 over the length of that beam. The compartment 23 is sealed by flexible strips 30 secured to the plate 27 and the body of the box 17. The suction box 17 has a connection 28 to a vacuum pump (not shown) by which suction may be applied through the compartment 20 and the perforations of a roll shell 29 to a paper web (not shown) directed over the outside of the shell.

As with the conventional design of suction box, the suction box 17 is installed with the edges carrying the sealing strips 18 formed to be parallel to the axis of the roll shell 29 when the box supported at its two ends deflects downwardly under its own weight with no suction applied (Figure 6). When suction is applied, the suction in the further compartment 23 acting on the beam 21 opposes the upward deflection of the box 17 arising from the suction and reduces the central lift of the box to an amount c (Figure 7). Wear of the centre of the strips 18 in operation is correspondingly reduced, so that when the suction is removed, the gap formed at the centre of the strips as the box 17 again deflects downwardly is narrowed down to an amount d (Figure 8). By suitable proportioning of the whole box assembly, this gap may in some cases be kept so narrow that it quickly becomes sealed by water on starting the roll in operation, so that the applied suction is soon effective to pull the box into full sealing contact with the shell.

Although the rolls are shown in Figures 1 to 8 as having shells of plain perforated metal, e. g., bronze, such

rolls being used for suction couches of paper machines and suction drum presses of paper-board machines, the invention may be applied to suction boxes for use with rubber-covered rolls as shown in Figures 9 to 12, such rubber-covered rolls being very frequently used in the press-sections of Fourdrinier machines.

The effective area of the further suction compartment is not necessarily equal to the projected area of the main compartment. For instance, in the case where the mouth of the main compartment is substantially wider than the body of the box (as in the accompanying figures), it may not be convenient to provide a further compartment materially different in width from the box; but the opposing deflecting force provided by the further compartment still cancels a substantial proportion of the main deflecting force.

Because of the reduction in the pressure between the sealing strips and the roll shell effected by the reduced deflection of the box under suction, substantially less power is required to drive the roll.

There may be more than one main suction compartment lengthwise of the mouth side of the box, to operate under different degrees of vacuum, e. g. by connecting each separately to its own source of vacuum.

In such case, the compartment producing the larger deflecting tendency on the box should be the one connected to the further suction compartment.

Apart from the advantages of the reduced deflection in operation by way of (a) the reduced wear at the centre of the sealing strips leaving narrower centre gaps when the suction is removed, and consequent ease of pulling the box back into position when the suction is re-applied, and (b) the reduction in driving power because of the reduced load on the sealing strips, the main box is subjected to less stress and may itself be made of lighter section.

Moreover, since the further compartment is subjected to suction by its connection with the main compartment and does not add to the vacuum requirements once the roll is in operation, no additional vacuum pump is required beyond the one serving the main compartment.

The invention may be readily applied to suction boxes of generally usual design as shown in Figures 9 and 10, in which a suction box 31 has a body 32 of hollow rectangular section and two suction compartments 33, 34 which apply suction through the perforations of a roll shell 35 having a rubber covering 36 to a paper web (not shown) directed over the outside of the roll 35, the area to which suction is applied being defined by mixed longitudinal sealing strips 37 and adjustable arcuate sealing strips (or "deckles") 38, 39. A longitudinal beam 40 of I-section is located inside the body section 32 with the ends only of one flange 40A bolted to pads 41 on the inner wall 42 adjacent to the main (or large) compartment 33. The opposite (outer) wall 43 is removable for insertion of the beam within the section. The point of attachment 44 of the end of the beam 40 is shown falling short of the end of the section 32 to allow for the end of the main compartment 33 to splay at 44 into line with a suction connection 45. Beyond this point, the beam is similarly splayed at 46 to provide its other flange 40B with a length more nearly equal to the length of the main compartment 33.

The other flange of the beam 40 lies clear of the removable wall 43 and is connected by studs 47 along its length passing through holes 48 in the wall 43 to a plate 44 spaced beyond the wall 43 and flexibly sealed at 50 round its entire periphery to the wall. The holes 48 are sealed by bellows 51. The space between the plate 49 and the wall 43 forms a further suction compartment 52 to be maintained under suction by pipe connections 53 (only one shown) traversing the box section from the main suction compartment 33.

The roll shell 35 has a hollow journal 54 with a bearing surface 55 resting in a half-bearing 56 and the

roll is driven by means of a gear 57. The suction connection 45 is rigidly attached to the body of the suction box 31 and supports the box through a screw adjustable spring 58 between the facings 59 of a guide 60 which is supported in a bracket 61 from the machine framing (not shown) and having a cap 62, whereby the guide may be readily removed to allow the suction box 31 to be withdrawn from the roll 35. The spring 58 urges the suction box 31 towards the shell 35 and the initial degree of contact between the sealing strips 37, 38, 39 is controlled by two adjusting screws 63 contacting the suction connection on either side of a control rod 64 which has a screwed portion 65 for lengthwise adjustment of the arcuate sealing strip 38. The other end of the suction box is similarly supported, but since there is no suction connection at the other end (not shown) a solid or closed up hollow member of similar exterior shape and size to the suction connection is rigidly attached to the end of the suction box body.

Under suction in the main compartment 33, the centre of the box section tries to deflect towards the mouth of the box and the plate 49 forming the far boundary wall of the further compartment 52 deflects in the same direction. But the centre of the bottom 43 of the box section forming the other boundary wall is urged in the opposite direction. The plate 49 being connected by the studs 47 to the free flange of the beam 40, the centre of the beam is caused to deflect towards the mouth of the box, but this deflection is not communicated to the box section, because the beam is only secured at its ends 41 to the box section. The beam thus provides a resistance to the deflection of the box section towards the mouth of the box as the net result of the application of suction to the further compartment 52. In other words, the distributed load resulting from suction is reduced, and the amount by which it is reduced is applied in equal parts at each end of the box, where it does not produce any material deflection of the box.

In Figures 11 and 12, a suction box 66 has two channels 67 externally along its sides, the channels 67 being secured to pads 68 on the section only at the ends of one flange 67A of each. The other flange 67B of each channel 67 extends beyond the integral wall 69 of the box section and a plate 70 across these flanges 67B is secured to them over its whole length by bolts 71. The plate 20 is flexibly sealed at 72 to the wall 69 of the box, from which it is spaced to form a further suction compartment 73. Pipe connections 74 across the box communicate with the main suction compartment 75. The plate 70 is transversely stiffened by T-angles 76, but it deflects over its length under the applied suction to an amount determined by the two channels 67 to which it is secured. This construction may be applied with but little modification of existing suction box designs.

What I claim is:

1. In a suction box structure for suction roll of a paper making machine, fixed longitudinal sealing strips adapted to contact the roll shell to define edges of a main suction compartment to which suction is directly applied, spaced support members defining a longitudinal beam secured at its ends only to the suction box structure, a further longitudinal suction compartment formed adjacent the main suction compartment and adapted to receive suction only from the main suction compartment by a communication between the two compartments, one boundary surface of this further compartment nearer the sealing edges at the mouth of the main compartment being constituted by a wall of the suction box structure itself and the other boundary surface farther from the sealing edges of the main compartment being connected to the longitudinal beam over the length of said beam.

2. A suction-box as in claim 1, wherein the longitudinal beam is disposed inside the suction box body.
3. A beam-like suction box structure for a suction roll of a paper-making machine comprising fixed longitudinal sealing strips along the edges of a main suction compartment of the box structure to contact the roll shell, the box structure being provided with a body portion of hollow generally rectangular section, two flanged beams lying externally alongside the hollow section and secured at the ends of one flange only of each to the sides of the box structure, the depth of the beams being such that the other flange of each extends beyond the depth of the hollow section, and a further longitudinal suction compartment in communication with the main suction compartment, one boundary surface of this further compartment being constituted by a wall of the hollow section and the other being connected over its length to the extending flanges of the two beams.
4. A suction-box as in claim 3, wherein the further boundary surface of the further suction compartment is a plate, and a flexible seal round the entire periphery of the plate between its edges and the outer wall of the hollow section complete the further compartment.
5. A suction-box as in claim 3, comprising a tube passing uninterruptedly through the hollow section to provide the communication between the main suction compartment of the box and the further suction compartment.
6. A beam-like suction box structure for a suction roll of a paper-making machine comprising fixed longitudinal sealing strips along the edges of a main suction compartment of the structure to contact the roll shell, the structure being provided with a longitudinal beam secured at its ends only to the suction box structure and with a further longitudinal suction compartment in communication with the main suction compartment, one boundary surface of this further compartment being constituted by a wall of the suction box structure and the other boundary surface farther from the sealing edges of the main compartment being connected to the longitudinal beam over the length of that beam, the box structure being of hollow generally rectangular section, the longitudinal beam being flanged, the ends of one flange thereof being secured to the inner wall of the hollow section, means defining holes being provided at intervals through the outer wall of the hollow section, connecting members passing through the holes between the other flange of the beam and the farther boundary surface of the further suction compartment, and sealing means closing the holes from that further suction compartment.
7. A suction box as in claim 6, wherein the farther boundary surface of the further suction compartment is a plate, and a flexible seal round the entire periphery of the plate between its edges and the outer wall of the hollow section complete the further compartment.
8. A suction box as in claim 7, wherein the outer wall of the hollow section is removable.
9. A suction box as in claim 6, wherein a tube passes uninterruptedly through the hollow section to provide the communication between the main suction compartment of the box and the further suction compartment.
10. A suction box as in claim 1, wherein the beam support for the box is external to the box.
11. A suction box as in claim 10, wherein the beam support is duplicated in the form of two flanged beams lying alongside the sides of the box.
